US0D1046836S

(12) **United States Design Patent** (10) **Patent No.:** **US D1,046,836 S**
(45) **Date of Patent:** **** Oct. 15, 2024**

(54) **ANTENNA**

(71) Applicant: **Shenzhen Hanyang Technology Co., Ltd.**, Guangdong (CN)

(72) Inventors: **Yang Huang**, Guangdong (CN); **Jialai Li**, Guangdong (CN); **Wenbang Li**, Guangdong (CN)

(73) Assignee: **Shenzhen Hanyang Technology Co., Ltd.**, Shenzhen (CN)

(**) Term: **15 Years**

(21) Appl. No.: **29/890,571**

(22) Filed: **Apr. 25, 2023**

(51) LOC (14) Cl. **14-03**

(52) U.S. Cl.

USPC **D14/230**

(57) **CLAIM**

The ornamental design for a antenna as shown and described.

DESCRIPTION

FIG. 1 is a front, right perspective view of the antenna;
FIG. 2 is a rear, left perspective view thereof;

FIG. 3 is a front view thereof;

FIG. 4 is a rear view thereof;

FIG. 5 is a left view thereof;

FIG. 6 is a right view thereof;

FIG. 7 is a top view thereof; and,

FIG. 8 is a bottom view thereof.

The broken lines shown on the drawings depict portions of the antenna that form no part of the claimed design.

1 Claim, 8 Drawing Sheets
